UNITED STATES PATENT OFFICE.

OTTO CZÁRÁN, OF GLENDALE, NEW YORK.

HARVESTER.

1,215,916.

Specification of Letters Patent. Patented Feb. 13, 1917.

Application filed March 9, 1914. Serial No. 823,601.

To all whom it may concern:

Be it known that I, Otto Czárán, a subject of the King of Hungary, and resident of Glendale, in the county of Queens and 5 State of New York, have invented certain new and useful Improvements in Harvesters, of which the following is a specification.

The present invention relates to grain 10 harvesters, and more particularly to the motor driven type.

One of the objects of the invention is to provide a harvester that carries two independent cutting mechanisms, whereby the 15 normal cut of the harvesters heretofore in use is doubled.

Another object of the invention is to arrange the several parts of the machine in such a manner that the machine can be folded to enable it to travel on narrow roads, etc.

A further object of the invention is to produce a reel, the several fans of which can be folded so as to contact with each other.

With these and other objects in view, 25 which will more fully appear as the nature of the invention is better understood, the same consists in the combination, arrangement and construction of parts hereinafter fully described, pointed out in the appended 30 claims and illustrated in the accompanying drawings, it being understood that many changes may be made in the size and proportion of the several parts and details of construction within the scope of the appended 35 claims without departing from the spirit or sacrificing any of the advantages of the invention.

One of the many possible embodiments of the invention is illustrated in the accompanying drawings, in which:

Figure 1 is a plan view of a grain harvester constructed in accordance with the present invention, the binding attachments and parts of the elevators being removed 45 in order to more clearly show the construction; Fig. 2 is a side elevation of the device shown in Fig. 1; Fig. 3 is also a side elevation of the machine looking from the other side; Fig. 4 is a front elevation of one of the reels; Fig. 5 is a side elevation of the reel in its open position; Fig. 6 is a similar elevation of said reel in its folded position; Fig. 7 is a side elevation of one of the frames carrying the reel; Fig. 8 is a similar 50 elevation of the other frame of the reel; Fig. 9 is a side elevation of the reel elevating

mechanism; Fig. 10 is a front elevation of the device shown in Fig. 9; Figs. 11 and 12 are details of construction of the device shown in Figs. 9 and 10; Fig. 13 is a plan view of a portion of one of the knives; Fig. 14 is a side elevation of the knife; Fig. 15 is a side elevation of the means for adjusting the height of the cut of the knife; Fig. 16 is a section taken through a detail of the device shown in Fig. 15; Fig. 17 is a plan view of the connecting means between the main frame of the apparatus and the front platform thereof; Fig. 18 is a side elevation of the device shown in Fig. 17; and Fig. 19 is 70 a central section taken on line 19—19 of Fig. 17.

In the drawings, the numeral 30 indicates the main frame of the machine, that is, preferably, rectangular in form, and supported 75 at its front portion by an axle 31, upon which the traction wheels 32 are mounted. At its rear end the frame is carried by a steering wheel 33, which is supported in a bifurcated standard 34, the upper end of 80 which is rotatably arranged in a bearing 35, the latter being carried by the frame 30. The standard 34 is provided with a sprocket wheel 36, over which runs a chain 37, the ends of which are attached to a steering 85 shaft 38, that carries a bevel gear 39, in mesh with a similar gear 40, the shaft 41 of the latter extending near to the operator's seat, where it has attached to it a bevel gear 41', in mesh with a bevel gear 141', upon the 90 shaft 141'' of which is mounted a hand-wheel 142'. Upon its forward end the frame carries a motor 42, preferably an internal combustion engine, the crankshaft of which may be connected in any manner known in 95 the art with a differential gear, one of the spindles of said differential gear carrying a worm 44, in mesh with a worm gear 45, that is in any suitable manner fixedly attached to the axle 31.

A substantially oblong-shaped bracket 46 is pivoted to the main frame at 47, near its front end, said bracket embracing, as it were, a box 48, in which the motor of the apparatus is mounted. At its front end the 100 bracket 46 carries a bearing 49, through which extends a spindle 50. Over the bearing 49 is drawn a sleeve 51, which is adapted to oscillate upon the said bearing. A flange 52 is formed upon the bearing 49, and against this flange abuts a flange 53 upon the sleeve 51. A ring 54, that embraces the

flange 53 and is fastened by screws 55, or otherwise, to the flange 52, prevents a disengagement of said sleeve from the said bearing, but allows of an oscillating movement of said sleeve relative to said bearing. 5 If it is intended to connect rigidly, for purposes hereinafter to be described, the sleeve 51 with the bearing, screw bolts 56, or other means, may be passed through registering holes in the two flanges mentioned. To the sleeve 51 are attached horizontally extending arms 57, which carry a similarly arranged supporting rod 58, upon which is oscillatably disposed an elevator platform frame 59. This platform is, as usual, oblong in configuration, and supports the platform canvas of the usual shape and construction (not shown in the drawings). The platform frame 59 rests on rollers 59', which 10 are in any suitable manner mounted upon the underface of and near the front edge of said platform. A transverse shaft 60 is oscillatably journaled in the platform frame 59 and provided with cranks 61, upon which 15 are mounted rollers 62. To one end of the shaft 60 is fixedly attached a lever 63, (Fig. 15), that is provided with a downwardly projecting extension 64, having an arc-shaped slot 65, and upon both of its sides 20 notches 66. In the slot 65 is seated a screw bolt 67, that is mounted upon the platform frame 59, a washer 68 being interposed between a nut 69 and the extension 64. This washer is provided with lugs 70, which are 25 adapted to enter the notches 66 in the extension 64. By means of this arrangement, the shaft 60 may be shifted and the platform raised, whereby the height of the cut is predetermined. If a deep cut is to be made, the 30 platform frame rests upon the rollers 59'. 40

The reciprocating knife of the cutting mechanism is indicated by the numeral 71, its actuating mechanism comprising a rotary shaft 72, having a crank 73 at its front 45 end, which is connected by means of a pitman 74 with a connecting rod 75, the latter being pivoted at 76 to the knife. The connecting rod 75 moves in a guide 77. Rotation is imparted to the shaft 72 from the 50 axle 31 in the following manner: Upon the axle 31 is mounted a spur gear 78, in mesh with a similar gear 79, that is carried by a countershaft 80, the latter carrying a sprocket wheel 81, over which runs a chain 55 82, in mesh with a sprocket wheel 83, that is loosely mounted upon a shaft 84. A bevel gear 85 on the shaft 84 meshes with a similar gear 86 upon a shaft 87. On this shaft is mounted a spur gear 88, in mesh with a 60 similar gear 89, the latter being carried by the spindle 50. A bevel gear 90 on this spindle meshes with a gear 91, the shaft of which carries a bevel gear 92, in mesh with a bevel gear 93 on a shaft 94, the latter being 65 rotatably mounted in the elevator frame

95. This elevator frame is hinged at 95' to the platform frame 59, the hinges and the pivot 76 being in alinement. A bevel gear 96 on the shaft 94 meshes with a bevel gear 97 on a transverse spindle 98, that carries 70 the bevel gear 99, in mesh with a similar gear 100 on the shaft 72. With the bevel gear 99 meshes also a gear 101 upon a spindle 102, by which is actuated a sprocket wheel and a chain 103, that drives the upper and lower aprons of the elevator mechanism, the platform apron, and the reel of the cutting mechanism. The sprocket wheel 83 is loosely mounted on the shaft 84, a connection between the said two elements being 75 80 made by any suitable clutch mechanism.

The reel associated with the platform 59 comprises a shaft 128, that is rotatably journaled in bearings 130, the latter being carried by frames 131 and 132. The frame 131 85 is mounted upon the inclined elevator frame 95, and the frame 132 upon the platform frame 59. The several fans and arms 133 of the reel are attached to disks 134, 135 and 136, the disk 135 being keyed to the shaft 90 128, while the disks 134 and 136 are loosely mounted thereon. The disks are provided with notches 137 upon diametrically opposite points thereof, which register with each other when the several fans and arms of 95 the reel are in their normal operative positions, shown in Figs. 4 and 5 of the drawings. When in such positions, spring 100 pressed latches 138 are adapted to be seated in said recesses, thereby keeping the disks, and thus the fans, in their proper positions. If it is intended to fold the reel, the said latches are disengaged from the disks, thus 105 permitting the several fans and arms of the reel to be folded into abutting positions, shown in Fig. 6 of the drawings. Upon the shaft 128 of the reel is mounted a bevel gear 139, in mesh with a bevel gear 140, that is carried by a vertically arranged spindle 141. This spindle is mounted in a shiftable frame 110 142, by which is carried the bearing 130 associated with the frame 131. The spindle 141 is provided with a key (not shown in the drawings), engaging a notch in a worm gear 143, that is held between a fork-shaped 115 extension 144 of the reel frame 131. With this worm gear meshes a worm upon a shaft 145, that is driven by the sprocket chain 103 above described. The bearing 130, in which the other end of the reel shaft is journaled, 120 is carried by a slide 147, that is mounted upon the frame 132. The lower ends of the shiftable frame 142 and of the slide 147 are provided with anti-friction rollers 148, normally resting upon bellrank levers 150, 125 which are pivoted at 151 to the frames 131 and 132. One end of each bellrank lever is engaged by a wire rope 152, that runs over sheaves 153, and is attached to a notched pulley 154, that is actuated in a manner 130

hereinafter to be described for the purpose of raising or lowering the reel according to the height of the grain to be cut.

The machine is provided with a further cutting and binding mechanism that is disposed upon one of the sides of the main frame 30. This mechanism comprises a platform 160, that is hinged at 161, 161 to an inclined elevator frame 162, the latter being pivoted upon a transverse shaft 163, that is journaled in a box-like frame 164. This frame is vertically shiftable in the main frame 30. For shifting the frame 164, the latter is provided with a plurality, in the present case four, racks 165, that are disposed in guides 166 upon the main frame and mesh with pinions 167. One pair of these pinions is mounted upon a shaft 168 and the other pair upon a shaft 169, both shafts extending transversely of the main frame. The shaft 169 is driven by a countershaft 170, the latter being actuated from the countershaft 80 by the intermediary of a chain 171, running over sprockets that are mounted upon said two countershafts. To the countershaft 170 are shiftabley attached two oppositely beveled gears 172 and 173, adapted to mesh with a gear 174, that is provided with oppositely bevelled faces, the gear 174 being keyed to the shaft 169. A suitable mechanism is provided for shifting as a unit the gears 172 and 173, thereby bringing one or the other of the same into mesh with the gear 174, resulting in a rotation of the shaft 169 in one or the other direction. The shaft 169 is connected with the shaft 168 in the following manner: A bevel gear 175 is keyed to the shaft 169, in mesh with a similar gear 176 upon a shaft 177, which carries a bevel gear 178, in mesh with a similar gear 179 upon the shaft 168. Between the gears 172 and 173 is disposed a bevel gear 172', upon the shaft of which is mounted a gear 173' meshing with a horizontally arranged bevel gear 180, that is mounted upon a vertically disposed shaft 181, the latter being provided with a worm 182, in mesh with a worm segment 182', that is fixedly attached to the bracket 46. From the foregoing it appears that, whenever the frame 164 is lowered or raised, the front end of the arms 57 will correspondingly be lowered or raised. The adjustments of the frame 164 and of the arms 57 are necessary according to the height of the grain to be cut. The platform 160 is provided with a knife 71, which is actuated by a shaft 183, which is provided with a crank 184, the latter being connected by a pitman 185 with a connecting rod 186, that is slidably arranged in a guide 187, the latter being mounted upon the elevator frame 162. The connecting rod 186 is pivoted at 188 to the knife, the pivot 186 being in alinement with the hinges 161.

The shaft 183 is actuated from the shaft 81 in the following manner: A bevel gear 189 is keyed to the shaft 183 and in mesh with a bevel gear 190, that is loosely mounted upon the shaft 163. The bevel gear 190 is made integral with a similar gear 191, the latter meshing with a bevel gear 192, that is fixedly attached to a shaft 194, which is journaled in the elevator frame 162. This shaft is provided with a key, that is seated in a notch of a bevel gear 195, the latter being held between a fork-shaped keeper 196 upon the main frame 30. The bevel gear 195 meshes with a similar gear 196', the shaft 197 of which is journaled in a bearing that is attached to the main frame 30, and carries upon its other end a bevel gear 198, in mesh with a similar gear 199, the shaft 200 of which extends to the shaft 84 and is there provided with a bevel gear 201, in mesh with the gear 85. The bevel gear 190 meshes furthermore with a bevel gear 202, upon the shaft 203 of which is mounted a sprocket wheel 204, meshing with a chain 205, which actuates the several aprons of the elevator mechanism and also the platform apron (not shown in the drawings). Upon the platform frame 160 are mounted frames (not shown), which are in all respects similar to the frames 131 and 132 that carry the reel of the front cutting mechanism. A transverse rod 60', carrying rollers 62', is provided upon the platform frame 160, the form and arrangement of the said rod and rollers being identical with the similar elements described in connection with the platform frame 59. Upon the grainward side of the platform frame 160 is provided a caster wheel 206, said wheel being rotatably mounted upon a vertical slide 207, that is arranged in guides and adapted to be shifted by means of a crank 208 in any suitable manner. The adjustment of the caster wheel relative to the platform frame becomes necessary when the platform is to be lifted to a height which cannot be attained by the use of the rollers 62'. Bell-crank levers, similar to those denoted by the numeral 150 in Figs. 7 and 8 of the drawings, are mounted upon the reel frames, 115 said levers being connected with wire ropes 209, which run over idlers 210, and are attached to a notched pulley 211.

The notched pulleys 154 and 211 are loosely mounted upon an arbor 212, that is journaled in the frame of the machine. To the arbor is fixedly attached a lever 213. Upon this lever are shiftabley mounted two spring pressed latches 214 and 215, the latch 214 cooperating with the notches in the pulley 154 and the latch 215 with the notches in the pulley 211. These latches are connected by rods 216 and 217 with bellcrank levers 218 and 219, respectively, said bellcrank levers being pivoted at 220 and 221, 130

respectively, to the lever 213. A bellcrank lever 222 is pivoted at 223 to the lever 213, and connected by means of a rod 224 with a latch 225, that is adapted to coöperate with the teeth of a gear segment 226, that is fixedly attached to the frame of the apparatus. Below the pulleys 154 and 211 is disposed a bracket 227, in which are shiftably arranged dogs 228 and 229, the dog 228 being adapted to coöperate with the notches in the pulley 154 and the other dog with the notches in the other pulley. The operation of the mechanism now described is as follows: When the latches 214 and 215 engage each with a notch in the pulleys 154 and 211, the positions of the reels on the two platforms are fixed. If it is intended to raise simultaneously both reels, the latch 225 is disengaged from the gear segment 226, and the lever 213 shifted in the direction of the arrow shown in Fig. 9 of the drawings, the latch being then engaged with one of the teeth of the gear segment 226, whereby the said reels are held in such raised positions. If it is intended to raise or lower only one of the reels, the dog coöperating with the pulley of the other reel is engaged with one of the notches in said pulley and the latch of the last named pulley disengaged therefrom. The latch 225 is then disengaged from the gear segment and the lever 213 shifted in one or the other direction as it is intended to raise or lower one of said reels.

The operation of the machine is as follows: Let us suppose that the parts of the implement are in the positions shown in Figs. 1 and 2 of the drawings, and it is intended to convey the same over a narrow road to the field where the grain is to be harvested. The parts of the apparatus are folded for this purpose in the following manner: First both reels are brought into the positions shown in Fig. 6 of the drawings, in which the fans of each reel abut against each other. The shaft 128 of the reel associated with the platform 160 is then disengaged from the bearing upon the frame 132, and swing around bodily the bearing 130 upon the frame 131, the latter bearing being obviously oscillatably disposed upon its slide. The reel is brought into substantially parallel relation with the side 30' of the main frame. The frame 132, which is hinged upon the platform frame 160, is then folded into parallel relation to said frame. The platform frame, with the parts carried thereby, is then brought into a substantially vertical position, to be held therein by any suitable fastening means. A bolt 230 is then passed through the elevator frame 162 and the frame 164, to prevent the former from oscillating relative to the frame 164. The reel associated with the front platform is then disengaged from its bearing 130 upon the frame 131, and swung around bodily around the bearing upon the frame 132, until it is brought into parallel relation to the side 30' of the main frame 30. The elevator frame 95 and its binding attachment is then brought into substantial vertical position by being shifted around its hinges 95', to be held in such position by any suitable fastening means. The bolts 56 are then engaged with the flanges 52 and 53 to prevent the front platform frame from oscillating. The front and side platforms with the parts carried thereby are then raised by rotating the countershaft 169 and the vertical shaft 181. The machine is then ready for transportation.

When the machine has reached the field, where the grain is to be harvested, obviously the operations now described are performed in their reverse order. It is to be observed that, before starting the operation of the implement, the platforms must be adjusted according to the cut to be obtained. The reels obviously are raised or lowered to positions that correspond to the height of the grain. To start the operation, the clutch is connected with the sprocket wheel 83.

It is to be observed that inasmuch as the device is provided with two cutting mechanisms, two elevators and binders, its output will be twice as large as that of any ordinary harvester. Although the harvester is provided with a cutter that is disposed on one of its sides, it is adapted to start the cut at any desired place of the field, due to the fact that it also possesses a cutting mechanism that is disposed in front of its main frame.

It is to be noted that with the machine herein described three different grains can be cut, more particularly grain that is standing upright, in which case the platforms are adjusted so as to rest upon the rollers 62 and 62' only; furthermore grain that lies almost on the ground, in which case the platforms are adjusted so as to rest upon their front rollers and the adjustable rollers 62 and 62'; and finally "heading" can be done, in which case the bolts 56 are engaged with the flanges 52 and 53, and the front platform raised by the intermediary of the worm 182 and worm gear segment 183 to the desired position. The elevator frame 162 is then by means of the bolt 230 rigidly fastened to the frame 164, and the platform 160 raised, and the caster wheel 206 adjusted to the proper position.

Inasmuch as the front platform swings around the spindle 50 and the pivots 47, and the rear platform swings around the shaft 163 and the hinges 167, the implement will automatically adapt itself to the inequalities of the ground.

What I claim is:—

1. In a harvesting machine, the combination of

tion with a main frame, of traction wheels and a steering wheel supporting the same, a harvesting mechanism carried by said frame at the front thereof, a harvesting mechanism attached to the side of said frame, both harvesting mechanisms being connected to the main frame in a manner so as to permit them to turn in any direction to adjust themselves to the inequalities in 10 the ground, and means common to both harvesting mechanisms for lowering or raising the same simultaneously and correspondingly at will in relation to said main frame.

2. In a harvesting machine, the combination 15 with a main frame, of traction wheels and a steering wheel supporting the same, a vertically shiftable auxiliary frame upon the said main frame, a harvesting mecha-

nism disposed upon one of the sides of said main frame and pivoted to said auxiliary 20 frame, a bracket pivoted to said main frame at the front end thereof, arms pivotally attached to said bracket, a second harvesting mechanism pivoted to said arms, and means in engagement with said auxiliary frame 25 and said bracket for simultaneously raising or lowering the same at will in relation to said main frame for the purpose specified.

Signed at New York, in the county of New York and State of New York, this 21st 30 day of Feb., A. D. 1914.

OTTO CZÁRÁN.
